UNITED STATES PATENT OFFICE.

EMIL FRANK AND JOHN KISSLING, OF RAHWAY, NEW JERSEY.

IMPROVEMENT IN CHURNS.

Specification forming part of Letters Patent No. 178,136, dated May 30, 1876; application filed April 21, 1876.

To all whom it may concern:

Be it known that we, EMIL FRANK and JOHN KISSLING, of Rahway, in the county of Union and State of New Jersey, have invented a new and useful Improvement in Rotary Churns, which improvement is fully set forth in the following specification, reference being had to the accompanying drawing, which represents a side elevation of our churn partly in section.

Our invention relates especially to that class of churning in which the tub and the dasher are adapted to revolve in opposite directions; and it consists in a peculiar mechanism for operating these parts; also in a novel arrangement of parts to permit of disconnecting and removing the churn from the working mechanism.

The stem of the dasher is stepped in the bottom of the tub, and passes loosely through the lid thereof, while it is geared to a driving-shaft, to which is geared also a counter-stem, which, in turn, is geared to the tub in such a manner that, by imparting a revolving motion to the driving-shaft, the dasher-stem and the tub are revolved in opposite directions. The bottom of the tub has a socket-piece on its under side, by means of which the tub is connected to the arbor of its driving-wheel, and the dasher-stem is made in jointed sections, so that by the socket-piece conjointly with the sectional stem the tub together with the dasher can readily be disconnected and removed from the working mechanism.

In the drawing, the letter A designates the tub of my churn, and B is a stem passing centrally through the tub, and to which is secured the dasher. The dasher is composed of a series of bent blades, C, and two heads, D D, which latter are firmly secured to the dasher-stem. The dasher-stem B is stepped in the bottom of the tub A, as at E, in any suitable manner, and it is passed loosely through the lid of the tub, while at its upper end the stem carries a gear-wheel, F, which meshes in a cor-

responding wheel, F', mounted on a shaft, G. This shaft has its bearings in a frame, N, and to it is secured a crank, H, for the purpose of turning it. Such shaft carries also a secondary gear-wheel, I, meshing with a gear-wheel, I', which is mounted on a stem, J, counter to the dasher-stem B. To the lower part or end of this counter-stem J is secured a cog-wheel, K', both the stem and the arbor of this wheel K' being stepped in the platform of the frame N. The wheel K' forms the driving medium of the tub A, and the upper part of its arbor is squared, as at a. Said wheel K' is connected to the tub by means of a socket-piece, L, formed or fastened on the under side of the tub bottom, this socket-piece being fitted and placed loosely on the square part a of the wheel-arbor, so that by simply lifting the tub it can be disconnected and removed. The dasher-stem B is made in two parts, which are jointed as seen at O, the joint being made in that part of the stem situated above the tub. It will be seen that when the dasher-stem is disconnected at the joint O, the tub A can be moved sidewise, so as to permit of lifting and removing it. When the tub has been removed, the dasher can readily be taken out of it by removing its lid.

What we claim as new, and desire to secure by Letters Patent, is—

The combination of the tub A and the dasher-stem B, stepped in the bottom of the tub, and made to pass loosely through its lid, the driving-gear F F' I I' K K', the shaft G, and counter-stem J, the whole being arranged and adapted to operate substantially as described.

In testimony that we claim the foregoing we have hereunto set our hands and seals this 11th day of April, 1876.
